United States Patent Office.

B. NEWBURY, OF COXSACKIE, NEW YORK.

Letters Patent No. 78,815, dated May 26, 1868.

IMPROVEMENT IN COOKING-STOVES.

The Schedule referred to in these Letters Patent and making part of the same.

TO ALL WHOM IT MAY CONCERN:

Be it known that I, B. NEWBURY, of Coxsackie, in the county of Greene, and State of New York, have invented a new and useful Improvement in Cooking-Stoves; and I do hereby declare that the following is a full, clear, and exact description thereof, which will enable others skilled in the art to make and use the same, reference being had to the accompanying drawings, forming part of this specification.

Figure 1 is a side view of a stove to which my improvement has been attached.

Figure 2 is a detail under side view of my improved attachment.

Figure 3 represents a modification of the same.

Similar letters of reference indicate corresponding parts.

My invention has for its object to improve the construction of cooking-stoves so as to make them more convenient in use; and it consists in attaching a hinged shelf to the rear part of the stove, and in the combination and arrangement of the parts, by which the shelf is connected to the stove.

A is a plate fitted upon the top of the rear part of the stove, and the forward edge of which fits upon the stove pipe cellar, to which it is secured by the removable yoke B. Upon the under side of the plate A are formed hooks a', which catch under the top of the stove, and brace the said plate securely in place. C is an arm formed upon or attached to the rear part of the plate A, and extending down along the back of the stove, as shown in fig. 1. D is a set-screw, passing through the lower end of the arm C, with its point resting against the rear side of the stove, so that the plate A may be readily adjusted to a horizontal position.

E is a shelf, which is hinged to the rear edge of the plate A, so that when not required for use it may be turned down along the rear side of the stove, so as to be out of the way. F is a brace-arm, which is pivoted to the plate A, and to a projection formed upon the arm C, so that the said brace-arm F may be turned out to support the hinged shelf E. In the case of new stoves the shelf F may be hinged to projections formed upon the rear part of the top of the stove, as shown in fig. 3. In this case the upper end of the vertical part of the brace-arm C should be pivoted to the under side of the top of the stove, and its lower end to a projection formed upon the rear side of the stove.

This latter construction I prefer for new stoves, but the construction first described enables the hinged shelf to be attached to any stove, no matter how long it has been in use.

I claim as new, and desire to secure by Letters Patent—

1. The combination of a hinged shelf, E, with the rear part of the stove, whether said shelf is hinged directly to the stove or to a removable plate attached to said stove, substantially as herein shown and described, and for the purpose set forth.
2. The combination of the removable plate A and removable yoke B with the hinged shelf E, substantially as herein shown and described, and for the purpose set forth.
3. The combination of the arm C and set-screw D with the plate A, substantially as herein shown and described, and for the purpose set forth.
4. The combination of the pivoted brace-arm F with the hinged shelf E, substantially as herein shown and described, and for the purpose set forth.

The above specification of my invention signed by me, this 24th day of January, 1868.

B. NEWBURY.
